UNITED STATES PATENT OFFICE.

ARTHUR M. WIGHT, OF NEW YORK, N. Y.

BOX.

1,043,378.

Specification of Letters Patent.

Patented Nov. 5, 1912.

Application filed June 14, 1909, Serial No. 502,021. Renewed March 15, 1911. Serial No. 614,701.

To all whom it may concern:

Be it known that I, ARTHUR M. WIGHT, citizen of the United States, residing at New York, in the county of New York and 5 State of New York, have invented a certain new and useful Improvement in Boxes, of which the following is a full, clear, concise, and exact description.

My invention relates to boxes or crates, 10 and more particularly to folding boxes such as are used for shipping purposes. Its object is to provide a shipping box which is cheap to manufacture, which will effectively resist both the internal and external pressure to which such boxes are subjected in use, and which may be quickly and easily assembled or reduced to its folding or knockdown form.

One feature of my invention relates to the 20 means by which the cover of the box is secured in place, and consists in providing the opposite ends of the box with flanges, preferably overhanging, inwardly extending flanges, one of said flanges being adapted to receive beneath the same one end of the cover and the other flange being adapted to receive beneath the same a key which extends transversely across the end of the box and overlaps the corresponding end of the 30 cover. The top and bottom portions of the box are preferably similarly constructed, the covers for the bottom and top of the box being interchangeable, and hence either may be considered as the top or the bottom cover 35 of the box, according to which is uppermost.

Another feature of my invention relates to the means whereby the several portions of the box intermediate the ends are prevented from bulging outwardly by the pressure exerted upon the interior of the box. 40 This feature of my invention consists in providing the sides of the box intermediate its ends with transverse vertical cleats which project beyond the edges of said 45 sides, and in securing upon the cover longitudinally extending blocks abutting said extending ends of the cleats, said cleats and blocks being thereby adapted to be secured together by nails or other fastening means.

These and other features of my invention 50 may be more readily understood by reference to the accompanying drawings, in which,

Figure 1 is a side elevation, partly in section and with parts broken away, of a ship-

ping box embodying my invention; Fig. 2 is a top plan view, partly in section and with parts broken away; and Fig. 3 is a fragmentary, sectional view on the line 3—3 of Fig. 1.

60

Like parts are designated by the same reference characters throughout the several views.

The sides A, A of the box may be of the usual construction and are shown as consisting of a series of strips 1 of veneer or similar material secured to transversely extending end cleats 2, 2 and an intermediate cleat 3. The sides A, A, may be secured to the ends B, B, of the box in the usual manner.

65

The frame of each of the ends of the box may be composed of the usual stiles 4, 4 to the inner faces of which are secured, at the top and bottom of the stiles, the bars or rails 5 and 6. The stiles 4 project at their ends beyond the top and bottom edges of the sides A, in order that the rails 5 and 6 may lie above or below, as the case may be, said top and bottom edges of the sides A. The 70 rails 5 thus form overhanging, inwardly projecting flanges at the ends of the top and bottom of the box.

75

The rails 5 are preferably of a greater depth or vertical thickness than the rails 6. 80 The ends of the stiles 4 are shown as projecting equal distances beyond the top and bottom of the box, and the rails 5 and 6 as secured with their longitudinal edges flush with the ends of the stiles. The rails 5 are 85

preferably of such depth that their surfaces which are adjacent the edges of the sides A of the box are flush therewith, and, since the rails 6 are of lesser depth than the rails 5, said rails 6 are slightly spaced from the 90 edges of the sides of the box. A channel is thus left between the sides of the box and the opposite faces of the rails 6 for purposes hereinafter set forth. The ends B are preferably so assembled that one each of 95 the rails 5 and 6 is at the top and the other at the bottom of the box, as shown in Fig. 1.

100

The covers C, C for the top and the bottom of the box, respectively, are shown as of similar construction, and interchangeable, 105 and hence, as hereinbefore stated, either may be considered as the top or bottom cover of the box. Each of said covers C may be formed of a series of slats or strips 7 of veneer or the like, secured to transversely 110

110

extending end cleats 8, 8. The cleats 8 are set in a slight distance from the ends of said strips 7 to provide ledges 9 either of which is adapted to be inserted beneath the rails 5 with the corresponding cleat 8 abutting against the rail 5, as shown at the left hand upper end and right hand lower end of Fig. 1. Each cover C is of such length that when one of its ends is thus inserted beneath the rail 5 the other end thereof extends approximately to the inner edge of the rail 6, thus enabling the cover to be readily set in place upon the box.

A key 10, in the form of a longitudinal strip of wood is removably inserted beneath the rail 6, said key overlapping the adjacent end or ledge 9 of the cover C. In other words, when the cover C is in position on the box one of the cleats 8 abuts against the rail 5, and the other cleat 8 is spaced from the end of the box and, together with said end of the box, the overhanging rail 6 and the underlying ledge 9, provides a channel, extending transversely of the box, for the reception of the locking strip or key 10. The strip 10 extends preferably across the entire end of the box, thus providing an efficient means for preventing outward displacement of the entire corresponding end of said cover. The cleats 8, 8 rest at their ends upon the side edges of the box and thus coöperate with said overhanging rails 5 and 6 and the key 10 to prevent the displacement of the cover C by either external or internal pressure upon the box.

Each cover C is preferably provided, intermediate the cleats 8, 8, with a cleat 11, the ends of which abut against the projecting ends of the cleats 3 upon the sides of the box. Spanning each end of the cleat 11 is a longitudinal block of wood 12 having a channel on its inner surface for the reception of the cleat 3, and securely fastened to said cover. The outer face of each block 12 abuts against a projecting end of a cleat 3. A nail or other fastening means is employed to secure the end of the cleat 3 to said block 12, thereby preventing the tops and sides of said box from bulging out.

Having thus described the preferred embodiment of the several features of my invention, what I claim is:

1. The combination with a box having an overhanging, inwardly projecting, top flange at each of its ends, of a box cover having one end thereof engaging beneath the flange at one end of said box, and a transversely extending longitudinal key interposed between the upper surface of the other end of said cover and the corresponding flange of said box.

2. The combination with a box having an overhanging, inwardly projecting, top flange at each of its ends, of a box cover having one end thereof engaging beneath the flange

at one end of said box, and the other end thereof terminating approximately flush with the inner edge of the flange at the corresponding end of said box, and a transversely extending, longitudinal key inserted beneath said latter flange and overlapping the upper surface of the end of the cover.

3. The combination with a box having an overhanging, inwardly projecting, top flange at each of its ends, of a cover supported at its sides upon the upper side edges of said box, said cover having one of its ends engaging beneath the flange at one end of said box and the other of its ends extending approximately to the inner edge of the flange at the other end of said box, and a removable key inserted beneath said latter flange, said key extending the entire length of said flange, and said key overlapping the upper surface of the end of said cover.

4. The combination with a box having an overhanging, inwardly projecting, top flange at each of its ends, of a box cover having cleats extending transversely across the upper surface of the cover at a slight distance from the ends thereof, thereby providing ledges at the ends of said cover, said cover, when in position on said box, having one of its ledges inserted beneath the flange at one end of said box with the edge of the corresponding cleat abutting said flange, and having the other of its ledges extending approximately to the inner edge of the flange at the other end of said box, thereby providing a channel partially underlying the corresponding flange, between the corresponding cleat and the end of the box, and a longitudinally slid able key fitting in said channel and extending transversely across the end of said cover.

5. The combination with a box having an overhanging, inwardly projecting, top flange at each of its ends, the under surfaces of the one and of the other of said flanges being approximately flush with and spaced apart from, respectively, the top side edges of the box, of a cover supported at its sides upon the upper side edges of said box, said cover having one of its ends engaging beneath said first named flange and the other of its ends extending approximately to the inner edge of said other flange, and a removable key inserted beneath said latter flange, said key extending the entire length of said flange, and said key overlapping the upper surface of the end of said cover.

6. A box comprising sides, ends, each of said ends having frames consisting of stiles and top and bottom rails secured upon the inner faces of said stiles, said rails projecting above and below the top and bottom edges, respectively, of said sides, a box-cover and a box-bottom, said cover and bottom being interchangeable and each having an end insertible beneath one of said rails, and lon-

gitudinal strips insertible beneath said other rails and overlying the adjoining ends of said cover and bottom.

7. A box comprising sides, ends, each of said ends having frames consisting of stiles and top and bottom rails secured upon the inner faces of said stiles, said rails projecting above and below the top and bottom edges, respectively, of said sides, one of each pair of rails being of a lesser depth than the other to provide a channel between the edges of the sides of the box and the opposite face of the rail, a box-cover and a box-bottom, said cover and bottom being interchangeable and each having an end insertible beneath the bottom of the top rail, respectively, having the greater depth, and longitudinal strips insertible beneath said other rails and overlying the adjoining ends of said cover and bottom.

8. A box comprising sides, ends, each of said ends having frames consisting of stiles and top and bottom rails secured upon the inner faces of said stiles, said rails projecting above and below the top and bottom edges, respectively, of said sides, one of each pair of rails being of a lesser depth than the other to provide a channel between the edges of the sides of the box and the opposite face of the rail, a box-cover and a box-bottom, said cover and bottom being interchangeable and each having cleats extending transversely across the outer surface thereof at a slight distance from its ends, thereby providing ledges at said ends, said cover and bottom when in position each having one of its ledges inserted beneath the rail at one end of said box with the edge of the corresponding cleat abutting said rail, and having the other of its ledges extending approximately to the inner edge of the rail at the other end of said box, and trans-

versely extending locking strips, one each for said cover and bottom, insertible beneath said last mentioned rails and each overlying the adjacent ledges at the end of the corresponding cover or bottom.

9. The combination with a box-frame consisting of sides and ends secured together, each of said ends having top and bottom rails projecting above and below the top and bottom edges, respectively, of said sides, of a box-cover and a box-bottom, said cover and bottom being interchangeable and each having an end insertible beneath one of said rails, and a longitudinal strip insertible beneath each of said other rails and overlapping the adjoining ends of said cover or bottom, respectively.

10. The combination with a box-frame consisting of sides and ends secured together, each of said ends having top and bottom rails projecting above and below the top and bottom edges, respectively, of said sides, one of each pair of rails being of a lesser depth than the other to provide a space between the edges of the sides of the box and the opposite face of the said rail of lesser depth, of a box-cover and a box-bottom, said cover and bottom being interchangeable and each having an end insertible beneath the bottom or top rail, respectively, having the greater depth, and a longitudinal strip insertible beneath each of the said rails of lesser depth and overlapping the adjoining end of said cover or bottom, respectively.

In witness whereof, I hereunto subscribe my name this eleventh day of June, A. D. 1909.

ARTHUR M. WIGHT.
